UNITED STATES PATENT OFFICE.

JOHN J. HEYS, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

GAGE MECHANISM.

1,286,317.

Specification of Letters Patent.

Patented Dec. 3, 1918.

Application filed July 28, 1917. Serial No. 183,363.

To all whom it may concern:

Be it known that I, JOHN J. HEYS, a citizen of the United States, residing at Lynn, in the county of Essex and State of Massachusetts, have invented certain new and useful Improvements in Gage Mechanisms; and I do hereby declare the following to be a full, clear, and exact description of the invention, such as will enable others skilled in the art to which it appertains to make and use the same.

The present invention relates to gage mechanism, and more particularly to gage mechanism employed in connection with sole pressing machines.

In sole pressing machines embodying a pair of coöperating forms, mechanism is conveniently provided for gaging the position of a sole lengthwise of the forms and it is desirable that this mechanism shall be constructed and arranged to accurately gage soles having differently shaped heel ends, as for example, block soles and died out soles.

It is the object of the present invention to provide an improved form of gage mechanism which may be conveniently adjusted to cause the accurate positioning of different styles of soles lengthwise of the coöperating pressing forms.

With this object in view the several features of the invention consist in certain novel features of construction, combinations and arrangements of parts hereinabove described and claimed, the advantages of which will be obvious to those skilled in the art from the following description.

In the accompanying drawings illustrating the preferred form of the invention, Figure 1 represents a side elevation, partly in section, of a sole pressing machine embodying the improved gage mechanism; Fig. 2 is a detail illustrating a side elevation of the gage mechanism in one operating position; Fig. 3 is a top plan view of the gage mechanism in the operating position shown in Fig. 2; and Fig. 4 is a detail illustrating a top plan view of the gage mechanism in another operating position.

The illustrated embodiment of the invention is conveniently shown in connection with a machine of the type disclosed in the application of John J. Heys, Serial No. 26,551, filed May 7, 1915. This machine

comprises a pair of coöperating pressing forms, indicated at 1 and 2, respectively, and arranged for relative movement to engage and mold a flat sole between them. The form 1 is adjustably mounted upon a head 4 in the usual manner, and the form 2 is supported upon a horizontally movable table 5, which, in turn, is carried by a vertically movable slide 6 to cause the proper movements of the form 2 toward and from the coöperating form 1. The table 5 is actuated in the usual manner through a lever 7 operatively connected with a cam disk 8, and the slide 6 is operated by a toggle lever of which one link is indicated at 9. The position of the flat sole is accurately determined with relation to the forms by a gage member which contacts with the heel end of the sole prior to the movement of the forms into a pressing position. After the sole has been positioned upon the lower form 2 it is firmly clamped by a gripping lever 10, pivoted at 11 and actuated by a second lever 12 during the horizontal movement of the table 5 to bring the form 2 into alinement with the coöperating form 1. This construction has been only briefly described herein as it is fully disclosed in the prior art.

The present machine is intended for operation principally upon two types of flat soles:—what are known as “block soles” in which the sole is roughly blocked out to the approximate size and shape and in which the heel end of the sole is characterized by a straight edge extending substantially at right angles to the length of the sole; and what are known as “died out soles” in which the sole is cut to a size and shape approximating more nearly the finished shape of the sole and in which the heel end of the sole is characterized by a curved line approximating the final curvature of the heel. It is desirable that a gage mechanism shall be provided for positioning both types of sole lengthwise of the forms, and that this mechanism may be conveniently adjusted to enable the operation of the machine upon either type of sole. To this end the present invention contemplates the provision of a gage member having a plurality of sole engaging faces each of which is constructed and arranged to engage and position the heel end of a particular style of sole, and means

for conveniently adjusting the gage member to bring any desired sole engaging face into operative position. In the illustrated embodiment of the invention the usual 5 gage block is employed and is provided with a heel gage pivoted thereon and having a pair of sole engaging faces and an actuating arm extending therefrom and provided with operating connections for adjusting the heel 10 gage to bring either sole engaging face into operative position.

The heel gage 20 is pivoted at 21 upon a block 23, pivoted at 24 upon a slide 25. The slide 25 is supported upon a rod 27 15 which is mounted in a head 28, adjustably supported upon the table 5 and carrying the gripping device 10 to cause a simultaneous and uniform adjustment of the heel gage and gripping device. The head 28 is 20 connected in the usual manner through an adjusting rod 30 with an adjusting device 31 at the front of the machine. The block 23 is provided with a depending tail 35 engaged by a spring pressed pin 36 to yieldingly maintain the lower face of the block in engagement with the upper face of the slide 25, as shown clearly in Fig. 1 of the drawings. The pin 36 is slidably supported in a recess formed in the slide 25 25 and is engaged at its rear end by a coiled spring 37. The block 23 is provided with oppositely disposed arms 40, between which the heel gage 20 is pivoted. As shown clearly in Figs. 2 to 4, inclusive, of the 30 drawings, the heel gage proper is provided with a pair of sole engaging faces which are indicated at 42 and 43, and are respectively V-shaped and straight to permit the gage to determine the position of died out soles 35 and block soles. When the heel gage is positioned as shown in Figs. 2 and 3 with the V-shaped face in operative position, the straight face of the gage is located at the under side in an inoperative position, and 40 when the straight face of the gage is located in an operative position, as shown in Fig. 4, the V-shaped gage is located at the top, as indicated in dot and dash lines in Fig. 2. With this construction a partial rotation of 45 the heel gage causes either face to be brought into an operative position and removes the other face into an inoperative position in which it does not interfere with the locating of the sole. In order to maintain the gage 50 in either operative position to which it is moved, the hub 45 of the gage is provided with depressions 46 and 47, which are arranged to be engaged by a pin 48, slidably supported in a boss 50 formed upon 55 the upper side of the block 23. The pin 48 is normally maintained in contact with the hub 45 by a spring 51, received in the recess in which the pin slides, as shown clearly in the drawings. In order to conveniently adjust the heel gage, operative connections are

provided which may be conveniently manipulated from the front of the machine. To this end the heel gage is conveniently secured to a rod 55 journaled in the arms 40 of the block 23, and having one end bent 70 laterally to form an actuating arm 60, as shown clearly in the drawings. The free end of the arm 60 is connected with an operating link 62 extending to the front of the machine and conveniently resting upon 75 the dial cover 63. In order to facilitate the adjustment of the gage and to insure that the gage may be readily moved from one operative position to another, it will be noted from an inspection of Fig. 2 of the 80 drawings that the arm 60 in either operative position of the gage is inclined to the link 62.

While it is preferred to employ the specific construction and arrangement of parts 85 shown and described, it will be understood that this construction and arrangement is not essential except so far as specified in the claims, and may be changed or modified without departing from the broader features of the invention. 90

The invention having been described, what is claimed is:

1. A gage mechanism for sole pressing machines, comprising a gage member adapted to contact with the sole edge and having a plurality of sole engaging faces, each of which is shaped differently to engage and position a particular style of sole, and mechanism under the control of the operator and 95 operatively connected with the gage member for adjusting the gage member to bring any desired sole engaging face into operative position. 100

2. A gage mechanism for sole pressing 105 machines, comprising a gage block, a heel gage pivoted thereon and having a pair of sole engaging faces, an actuating arm extending from the heel gage, and means operatively connected with the arm for adjusting 110 the heel gage to bring either sole engaging face into operative position.

3. A gage mechanism for sole pressing machines, comprising a gage block, a heel gage pivoted thereon and having, respectively, a straight sole engaging face and a V-shaped sole engaging face, and mechanism 115 operatively connected with the heel gage for adjusting the gage to move either of the faces into an operative position. 120

4. A gage mechanism for sole pressing machines, comprising a gage block, a heel gage pivoted thereon and having, respectively, a straight sole engaging face and a V-shaped sole engaging face, mechanism 125 operatively connected with the heel gage for adjusting the gage to move either of the faces into an operative position, and means for retaining the gage with either sole engaging face in operative position. 130

5. A gage mechanism for sole pressing machines, comprising a gage block having a pair of oppositely extending arms, a heel gage pivoted between the arms and having a plurality of sole engaging faces, an actuating arm secured to the heel gage, and an operating link connected to the arm and extending to the front of the machine in convenient relation to the operator.
- 10 6. A gage mechanism for sole pressing machines, comprising an adjustable slide, a gage block pivoted upon the slide, means for yieldingly maintaining the block in contact with the upper face of the slide, a heel gage pivoted to the block and having a plurality

of different shaped faces adapted to locate soles of different shapes, and means under the control of the operator for adjusting the heel gage.

7. A gage mechanism for sole pressing 20 machines, comprising a gage block, a heel gage pivoted thereon and having a pair of sole engaging faces, an operating link extending to the front of the machine, and an actuating arm connecting the link and heel 25 gage and inclined to the link when the heel gage is positioned with either one of the sole engaging faces in operative position.

JOHN J. HEYS.
